[57] CLAIM

The ornamental design for artificial nail or the like, substantially as shown and described.

DESCRIPTION

FIG. 1 is a perspective view of an artificial nail or the like showing my new design;

FIG. 2 is a front elevational view;

FIG. 3 is a right side elevational view;

FIG. 4 is a top plan view;

FIG. 5 is a bottom plan view;

FIG. 6 is a left side elevational view;

FIG. 7 is a rear elevational view;

FIG. 8 is a sectional view taken along line 8—8 in FIG. 7;

FIG. 9 is a front elevational view of an artificial nail or the like showing a second embodiment of my new design;

FIG. 10 is a right side elevational view thereof;

FIG. 11 is a left side elevational view thereof;

FIG. 12 is a top plan view thereof;

FIG. 13 is a bottom plan view thereof;

FIG. 14 is a rear elevational view thereof;

FIG. 15 is a sectional view taken along the line 15—15 in FIG. 14;

FIG. 16 is a rear elevational view of an artificial nail or the like showing a third embodiment of my new design which varies only in the finish of the rear surface; and FIG. 17 is a rear elevational view of an artificial nail or the like showing fourth embodiment of my new design with a polished rear and vector marking.

The broken line showing of a finger in FIG. 1 is for illustrative purpose only and forms no part of the claimed design.
